BULLETIN BOARD

Melburn O. Simmons, 675 Duane St.,
Glen Ellyn, Ill. 60137

Filed Dec. 2, 1969, Ser. No. 20,331

Term of patent 14 years

Int. Cl. D20—03

U.S. Cl. D96—12

FIG. 1 is a front elevational view of a bulletin board showing my new design, the rear being plain and unornamented;

FIG. 2 is a top plan view thereof;

FIG. 3 is a bottom plan view thereof; and

FIG. 4 is an elevational view taken from one side thereof.

The rear side of the bulletin board is plain.

I claim:

The ornamental design for a bulletin board, substantially as shown.
